HOT WATER HEATING SYSTEM

Thomas E. King, Westfield, N. J., assignor to
 Hitchings & Company, Elizabeth, N. J., a corporation of New Jersey

Application March 9, 1931, Serial No. 521,372

1 Claim. (Cl. 237—60)

This invention relates to heating systems but more particularly to the hot water type.

One of the objects of the invention is to provide heating apparatus of this type which is simple and economical in construction, dependable and efficient in operation, and in which the heater element may be located above the radiating coils.

Another object is to provide a system of this type in which the temperature and volume of flow of the water vary with the requirements.

Other objects, general and particular, will be best understood by reference to the accompanying drawings showing an illustrative embodiment in which:

Fig. 1 is a diagrammatical view of a heating system constructed in accordance with the present invention, and

Fig. 2 is an enlarged detail sectional view of a tank of the system shown in Figure 1.

The apparatus forming the subject matter of the present invention will be referred to as the percolator type in view of the similarity of action to the well known percolator in which water heated in a receptacle moves upwardly upon the formation of steam in such receptacle through a pipe leading therefrom and discharges into an elevated receptacle from which it flows by gravity to perform its function. The particular function in the present instance is to supply this hot water to a radiating system.

Referring particularly to Fig. 1 of the drawings, a hot water heater as 5 of suitable type is provided with the usual fire box and boiler. Leading upwardly from the top of the boiler is a hot water outflow pipe 6 which has its upper end connected to an elevated tank 7 which will hereinafter be referred to as the percolating tank.

This tank 7 is provided with a transverse partition 8 which divides it into an upper compartment 9 (Fig. 2) and a lower compartment 10, and the pipe 6 leads into the upper compartment near the top thereof. From this compartment 9 near its bottom leads a pipe 11 which conducts the hot water to the radiating system. The form and arrangement of this system will depend largely upon the space to be heated. The cool water returns from this system by a pipe 12 leading to a receptacle 13 associated with the tank, whence it flows into the lower compartment 10 of the tank 7 and then returns to the boiler of the heater by way of the pipe 14.

Referring to Fig. 2, the tank 7 is of the vertical type, open at the top, and provided with a cover 15 bolted or otherwise fastened thereto.

The pipe 6 carrying the hot water from the boiler communicates with the upper compartment 9 in the manner described and may be connected to the tank in any suitable manner as by a coupling 16. From the opposite side of this compartment near the bottom thereof leads the hot water outflow pipe 11 which may also be connected to the tank in any suitable manner as by a coupling 17. Within this compartment 9 is a steam outlet pipe 18 having its open upper end near the top thereof. This pipe 18 leads from the compartment 9 to the receptacle 13 where it is connected to the upper end of a coil 19 therein. The lower end of this coil is coupled to a pipe 20 which leads into the tank 7 and communicates with the lower compartment 10.

The cool water returning from the radiating system in the pipe 12 enters the receptacle 13 preferably at the bottom thereof and, after passing about the coil 19, leaves the receptacle substantially at the top thereof through a pipe 25 and flows into the lower compartment 10 of the tank 7. This pipe 25 may be extended toward the bottom of the compartment. At the right of the compartment 10 are shown a water level gauge as 30, a safety valve as 31 and an air vent as 32 communicating therewith. Water entering the compartment 10 from the pipe 25 and condensed steam from the pipe 20 mix in the bottom of the tank 7 and flow back to the boiler through the pipe 14. The portion of the apparatus so far described in detail will be herein-after referred to as the percolating system to distinguish it from the radiating system.

Referring again to Fig. 1, the radiating system in the present apparatus is shown in the lower right hand portion of the drawings. The construction and arrangement of this system will naturally be very materially varied according to the requirements, but the form here shown will serve to illustrate the general principles. This radiating system preferably operates by the thermo-syphon method of circulation. Warm water in the riser pipe 35 passes to the main distributing pipe 36 and then through leads as 37 to radiating units 38. The cool water from these units 38 returns through leads 39 to the main return pipe 40 and then passes into the pipe 41. In order to provide a closed coil and thus obtain thermo-syphon circulation, the pipes 35 and 41 are connected by a pipe 42. It will be evident that differences in temperature of the water in different portions of this coil will cause a substantially continuous circulation therein.

Hot water from the percolating system is in-

duced into the radiating system through the pipe 11 which is connected to the lower end of the riser pipe 35. At the same time cool water is withdrawn from this radiating system by means 5 of the pipe 12 which is connected to the inner end of the return pipe 41. The pipes of the main coil, here designated 35, 36, 40, 41 and 42, are of larger diameter than the pipes 11 and 12 of the percolating system so that a relatively small quantity 10 of very hot water will be discharged by the pipe 11 into the relatively large quantity of cool water in the pipe 35.

In the operation of the heating system, hot water from the boiler of the heater 5 will move 15 upwardly in the pipe 6 as soon as the water in the boiler has become sufficiently hot to cause steam to form therein and to collect at the top of such boiler. This may result from the difference in weight of the columns of water in the 20 pipes 6 and 14 due to the presence of the steam bubbles in the pipe 6, the pipe 14 being completely filled with water. The water and the steam passing upwardly therewith enter the compartment 9 of the tank 7 where the water falls to 25 the bottom of this compartment. The steam entering this compartment passes into the open upper end of the pipe 18 and then downwardly in this pipe to the receptacle 13 where it passes through the coil 19 in which it is condensed by 30 the action of the cool water circulating through this receptacle. The condensed steam flows from the coil 19 through the pipe 20 into the lower compartment 10 of the tank 7.

The hot water deposited in the compartment 35 9 of the tank in the manner described flows downwardly through the pipe 11 to the radiating coil. At the same time, the cool water returning through the pipe 12 enters the receptacle 13 and overflows therefrom through the pipe 25 into the lower compartment 10 of the tank 7. It is this 40 returning cool water which acts to condense the steam in the coil 19 and at the same time the coil acts to partially reheat this cool water which is somewhat further reheated by mixing with the 45 condensed steam flowing from the pipe 20. The partial reheating of the water prior to its return to the boiler through the pipe 14 is advantageous as this water does not reduce the temperature of the water within the boiler as greatly as would be the case if the water in the pipe 12 were directly returned thereto. This enables steam to 50 form more frequently within the boiler with the same amount of heat from the fire box and thus

a greater flow of hot water is provided to the radiating system for the amount of fuel used. The length of the intervals between periods of flow of hot water into the compartment 9 depends mainly on the temperature of the water returning to the boiler and the intensity of the heat supplied to the boiler by the fire box. Although the flow of water within the percolating system is periodic, the thermo-syphon circulation in the radiating coil is practically continuous and a substantially even heat is delivered to the space to be heated.

It will be evident that in a combined system such as described, the temperature and volume 15 of flow of the water in the radiating system will vary with the requirements. The entire apparatus is simple, durable and economical in construction and dependable and efficient in operation. The heater may be located above the radiating coils and this is often advantageous. 20

As many other embodiments of the apparatus may be made without departing from the scope of the invention, it is to be understood that all matter herein set forth or shown in the accompanying drawings is to be interpreted as illustrative and not in a limiting sense. 25

I claim:

In a hot water heating system, a heater, a tank located above said heater, a transverse partition in said tank dividing the tank into upper and lower compartments, means for conducting hot water and steam from the top of said heater to said upper compartment; and means for conducting hot water from said upper compartment, a receptacle associated with said tank, a 35 steam collecting pipe leading from said upper compartment to said receptacle, a condensing coil in said receptacle connected to said steam collecting pipe and leading to said lower compartment, a cool water return pipe leading 40 to said receptacle, a pipe leading from said receptacle to said lower compartment to carry the water to said lower compartment after it has passed about said coil and been partially heated by heat exchange therewith, the outlet of said 45 return pipe being below the inlet of said means for conducting hot water from said upper compartment, and an outflow pipe leading from said lower compartment to carry the partially heated water therefrom to said heater below said outlet. 50
